United States Patent Office.

AUGUSTUS STANLEY, OF NEW BRITAIN, CONNECTICUT.

Letters Patent No. 97,455, dated November 30, 1869; antedated November 20, 1869.

IMPROVEMENT IN BIT-STOCK.

The Schedule referred to in these Letters Patent and making part of the same

To all whom it may concern:

Be it known that I, AUGUSTUS STANLEY, of New Britain, in the county of Hartford, and State of Connecticut, have invented a new and improved Bit-Stock; and I do hereby declare that the following is a full, clear, and exact description thereof, which will enable others skilled in the art to make and use the same, reference being had to the accompanying drawings, making a part of this specification, in which—

Figure 1 is front elevation of my invention, with a sectional view of the head.

Figure 2 is a front elevation of the socket-end of the bit-stock before the pawl and spring are inserted.

Figure 3 is a side elevation of the same, with the pawl and spring attached.

Figure 4 is a front elevation of the pawl.

Figure 5 is a side elevation of the same.

Similar letters of reference indicate like parts.

My invention relates to bit-stocks, and consists in the construction and arrangement of the various parts, as will be fully described hereinafter.

The body A of the bit-stock and its head B can be of any suitable construction, of the ordinary styles.

The socket-end o of the bit-stock is also of nearly the ordinary style.

I construct the pawl or lever b much shorter than an ordinary pawl.

The end that engages with the bit m is made of a circular form, instead of the usual square or hooked form.

As the socket a is of ordinary length, and it would be inconvenient to have the end of the pawl or lever b project below the socket a, I am obliged to construct the pawl of the peculiar shape and length described and shown, in order to make it operate in the space desired, and, at the same time, to be out of the way in use.

The pawl or lever b is raised by spiral spring c, and pivoted to arms h h by pivot i.

One end of spiral spring c rests in cavity d, and the other is held in place by the small tenon k, on the under side of the pawl or lever b, which pawl b is

placed with the pawl-end upward, which position is the reverse of the ordinary pawl in bit-stocks.

e designates a cavity to receive the end of the pawl b.

A suitable notch is made in the usual place in the shank of bit m, which bit m is placed in the socket when the pawl-end of lever b enters the above-mentioned notch, and secures the bit m rigidly in its place, as shown by the broken lines in fig. 3.

As the fulcrum or pivot i of the lever or pawl b is below the pawl-end, any attempt to withdraw the bit m, without raising the pawl b, will only cause the pawl b to press the bit m more closely, and thus hold it firmer in its place, without any assistance of the spiral spring c, which spring c is simply to throw the pawl b into the notch in the bit m, and not to hold it in its place, and consequently the spring c can be made very light.

In the ordinary manner of attaching a lever-pawl to a bit-stock, the pawl is below the pivot, and therefore it will often rise, and allow the bit to withdraw, by simply pulling on the same, and therefore the spring, either spiral or flat, must be strong and stiff, to hold the pawl in its place.

By my invention, I produce an article for a bit-stock, whereby the inconvenience and annoyance of the bit withdrawing when in use are entirely overcome. It can be made equally as cheap as others, and is much more durable and less liable to get out of repair.

I do not claim simply placing the pawl-end above the pivot, as the same can readily be done in bit-stocks where there is sufficient room to make the pawl of any desired length.

What I claim as new, and desire to secure by Letters Patent, is—

As a new article of manufacture, the herein-described brace, consisting of the head B, body A, socket a, inverted pawl b, arms h h, spring c, and pivot i, the whole constructed and arranged substantially as shown and described, and for the purposes set forth.

Witnesses: AUGUSTUS STANLEY.

JAMES SHEPARD,
HENRY S. WALTER.
